CLAIM

The ornamental design for toaster oven, as shown and described.

DESCRIPTION

FIG. 1 is a perspective view as seen from the top, front, and right side of a toaster oven showing my new design;
FIG. 2 is a front elevational view thereof;
FIG. 3 is a top plan view thereof;
FIG. 4 is a rear elevational view thereof;
FIG. 5 is a right side elevational view thereof;
FIG. 6 is a left side elevational view thereof;
FIG. 7 is a bottom plan view thereof;

FIG. 8 is a perspective view as seen from the top, front, and right side of a second embodiment toaster for a toaster oven showing my new design;
FIG. 9 is a front elevational view thereof;
FIG. 10 is a top plan view thereof;
FIG. 11 is a rear elevational view thereof;
FIG. 12 is a right side elevational view thereof;
FIG. 13 is a left side elevational view thereof; and,
FIG. 14 is a bottom plan view thereof.

The broken lines in FIG. 1 showing the power cord are used for illustrative purposes only and form no part of the claimed design.

The broken lines in FIG. 8 showing the power cord and the control knobs are used for illustrative purposes only and form no part of the claimed design.
